UNITED STATES PATENT OFFICE.

JOHN L. BURTON, OF HAMLET, NORTH CAROLINA.

SWITCH-LOCK.

1,345,580.

Specification of Letters Patent.

Patented July 6, 1920.

Application filed July 24, 1919. Serial No. 313,060.

To all whom it may concern:

Be it known that I, JOHN L. BURTON, a citizen of the United States, residing at Hamlet, in the county of Richmond and State of North Carolina, have invented certain new and useful Improvements in Switch-Locks, of which the following is a specification.

This invention relates to railway switches and more especially to safety devices for use in connection therewith, the invention having as one of its principal objects to provide a lock for securing the switch points in either open or closed position.

The invention has as a further object to provide a lock which, even though the mechanism for throwing the switch should, as frequently occurs, become broken or disarranged by accident, will, nevertheless, operate to lock the switch.

The invention has as a further object to provide a lock which will prevent the switch points from being moved either by accident or with malicious purpose.

And the invention has as a still further object to provide a lock which can be applied to substantially any conventional type of switch but which will, by preference, be applied at the time the switch is put in.

Other and incidental objects will appear hereinafter.

In the drawings:

Figure 1 is a perspective view showing my improved switch lock applied to a conventional type of railway switch, parts being broken away and shown in section.

Fig. 2 is a transverse section through one of the switch ties and one lock casing of the device, and

Fig. 3 is a perspective view showing one of the lock casings in detail.

Referring now more particularly to the drawings, I have illustrated my improved lock in connection with a conventional railway switch. The ties are indicated at T and overlying the ties are rails which are connected with the ties by ordinary fastening means such as spikes S. Associated with the rails are the switch points P and in Fig. 1 I have shown diagrammatically the mechanism for throwing these points from a switch stand SS disposed at one side of the track, the points being connected by the

usual bridle bar B so that they will move in unison.

Coming now more particularly to the subject of the present invention, I employ companion oblong casings 10. These casings are seated in suitable recesses cut in the tie and are arranged with their outer sides lying flush with one side face of the tie. Overlying the casings are removable overhanging chair plates 11 which form closures for the casings and seat flat against the upper face of the tie. Depending from said plates are flanges 12 coacting with the end and side walls of the casings for rigidly holding the plates against both longitudinal and transverse movement. Adjacent corresponding ends, the plates are cut away at their upper sides to provide seats 13 for the bases of the rails R while the opposite end portions of the plates form wear blocks 14 raised with respect to the seats and slidably supporting the switch points P. Upstanding from the plates at the outer sides of the rail seats are spaced flanges 15 engaging over the rail bases while similar flanges 16 rise from the plates at the outer ends of the wear blocks and form stops for the switch points. Securing the chair plates at their ends are spikes driven into the tie and engaging over the overhanging end portions of the plates. At their outer sides the casings are provided with suitable drain openings 17.

Normally projecting through suitable openings in the wear blocks 14 of the chair plates are bolts or stops 18 which may be integrally formed at their lower ends with tail portions providing flat springs 19 curved toward their outer ends downwardly and inwardly to seat flat against the bottom walls of the casings to which walls the end portions of the springs are suitably secured. As will be clear, the springs will normally project the stops through the wear blocks while, at the same time, the stops may, nevertheless be retracted. To insure proper projection of the stops, should the springs 19 become broken, supplemental springs 20 are provided. These springs are arranged directly beneath the stops to bear against the bottom walls of the casings and are held by suitable centering lugs.

Journalized through the side walls of the casings are rock shafts 21 provided at their

outer ends with crank arms 22 and fixed upon said shafts within the casings are cams 23 each provided with a flat end face 24. Swingly connected to the crank arms 22 are rods or links 25 which are pivotally secured to a lever 26 common to both of the links. The lever is pivotally mounted upon a plate secured in any approved manner to the adjacent face of the tie and said lever 10 is provided at its free end with a hasp 27 engageable over a staple 28 driven into the tie, this staple being designed, of course, to receive a lock securing the lever against movement. As will be clear, the lever 25 15 may be swung for rocking the cams 23 and it is now to be observed that these cams are so set upon the rock shafts that when the lever is swung in either direction, one cam will be moved to release one of the stops 20 28 while the other cam will be moved to retract the other stop, the flat faces 24 on the cams being provided for limiting the cams in their turning movement to active position. As will be seen, the flat face of 25 that cam which is turned to retract one of the stops will be brought into contact with the tail portion of said stop for thus arresting turning movement of both of the cams. This construction provides an arrangement 30 whereby it may be easily determined when the lever 25 has been swung sufficiently as well as an arrangement whereby, when the lever is released from its hasp 28, the cams will be locked against accidental pivotal 35 movement.

In Fig. 1 of the drawings I have shown the switch set in normal closed position. When so set it will be observed as shown at 40 the left of the figure, that one of the stops 18 will project in front of the adjacent switch point for thus blocking movement of both of the switch points while the other stop will be depressed. Furthermore, the lever 25 will be disposed in vertical position 45 so that its hasp 27 may be engaged over the staple 28 and a lock connected to the staple for thus securing the switch closed. Either accidental or malicious opening of the switch will consequently be prevented. Furthermore, 50 it is to be noted that injury to the switch actuating mechanism can not serve to open the switch. However, when it is desired to operate the switch it is simply necessary to disengage the lock from the staple 55 28 when the lever 25 may be swung to depress the active stop, as shown at the left of Fig. 1 and free the other or inactive stop, either block when in active position being freely movable downwardly past its 60 adjacent switch point. The switch points may then be moved in the ordinary manner either from an adjacent switch stand, as shown at SS, or from a distant signal tower. Upon the release of the inactive 65 stop of the switch lock this stop will, as

particularly brought out at the right of Fig. 1, be projected by its tail portion against the base of the adjacent switch point. Consequently, when the switch is thrown, said stop will, as soon as the switch point 70 clears the stop, be moved outwardly behind the switch point for locking the switch open. This, of course, would also hold good in connection with the other stop for locking the switch closed. It will accordingly be seen that I provide a very effective type of switch lock which, even though the switch operating mechanism should be rendered inoperative, will still function to securely lock the switch. 75

Having thus described the invention, what is claimed as new is:

1. A switch lock including a switch point stop provided with a tail forming a spring normally projecting the stop to active position, and means adapted to act upon the tail of the stop to retract the stop. 80
2. In a railway switch lock, the combination with a switch point, of a stop having main and auxiliary springs for projecting 90 the stop to active position blocking movement of the switch point, and means for retracting the stop. 95
3. A switch point lock including companion switch point stops normally urged to active position, and means for releasing either stop and retracting the other simultaneously. 100
4. A railway switch lock including a switch point stop, and a cam mounted below the stop and rotatable to shift the stop to inactive position. 105
5. A railway switch lock including a switch point stop, means normally urging the stop to active position, and means arranged to engage the first means for retracting the stop. 110
6. A railway switch lock including a switch point stop, means normally urging the stop to active position, means arranged to engage the first means for retracting the stop, and means carried by said second mentioned means to seat against the first means for arresting movement of said last mentioned means when the stop is retracted. 115
7. A railway switch lock including a switch point stop, means normally urging the stop to active position, and a cam arranged to engage the first means for retracting the stop and provided with a flat face to seat against the first means for arresting movement of the cam when the stop is retracted. 120
8. A railway switch lock including a switch point stop, a spring normally urging 125 the stop to active position, and means arranged to engage the spring for flexing the spring and retracting the stop. 130
9. A railway switch lock including companion switch point stops normally urged to

active position, and cams simultaneously rotatable for releasing either stop and retracting the other.

10. In a switch point lock, the combination of a casing, a switch point stop having means secured within the casing and supporting the stop, said means being adapted to normally project the stop from the casing in active position, and means supported by 10 and housed within the casing for retracting said stop.

11. In a switch point lock, the combination of a casing, a chair plate closing the casing, a switch point stop normally projecting

from the casing through said plate in active 15 position, and means within the casing for retracting said stop.

12. In a switch point lock, the combination of a casing, a spring secured within the casing and provided with a switch point stop 20 normally supported by the spring to project from the casing in active position, a rock lever journaled upon opposite walls of the casing, a cam carried by said lever within the casing and movable to retract the stop, 25 and means for rocking the lever.

In testimony whereof I affix my signature.

JOHN L. BURTON. [L. S.]
